UNITED STATES PATENT OFFICE

ALBERT S. HOWELL, OF CHICAGO, ILLINOIS, ASSIGNOR TO THE BELL & HOWELL COMPANY, OF CHICAGO, ILLINOIS, A CORPORATION OF ILLINOIS

DESIGN FOR A PHOTOGRAPHIC EXPOSURE METER CASE

Application filed June 25, 1930. Serial No. 36,167. Term of patent 14 years.

To all whom it may concern:

Be it known that I, ALBERT S. HOWELL, a citizen of the United States, residing at Chicago, in the county of Cook and State of Illinois, have invented a new, original, and ornamental Design for a Photographic Exposure Meter Case, of which the following is a specification, reference being had to the accompanying drawing, forming a part hereof.

In the drawing—

Figure 1 is a side elevation of a photo-

graphic exposure meter case embodying my new design;

Figure 2 is a front elevation of the same; and

Figure 3 is a top plan view of the same.

I claim:

The ornamental design for a photographic exposure meter case as shown.

In witness hereof I hereunto affix my signature this 20th day of June, 1930.

ALBERT S. HOWELL.
